(57)

CLAIM

The ornamental design for a warning sign, as shown and described.

DESCRIPTION

5. Warning sign

5.1 : Front**5.2** : Back**5.3** : Top**5.4** : Right

The left view is omitted because it is identical with the right view; the bottom view is omitted because it is identical with the top view; the dot-dash broken lines define the boundaries of the claimed design and form no part of the claimed design; the broken lines inside the boundaries form part of

(Continued)

the claimed design; any other broken lines illustrate portions of the warning sign and form no part of the claimed design.

1 Claim, 4 Drawing Sheets
